Attorney

UNITED STATES PATENT OFFICE.

GUNELIUS SKAVSTRAND, OF CHICAGO, ILLINOIS.

CASING.

Application filed November 14, 1925. Serial No. 69,150.

My present invention pertains to casings, and contemplates the provision of a casing designed more especially for the safe carriage and protection of spirit level such as 5 ordinarily used by carpenters; the casing being characterized by a closure that is not liable to casually open and adapted to be expeditiously and easily opened as when it is desired to remove the spirit level from 10 the casing for use.

To the attainment of the foregoing, the invention consists in the improvement as hereinafter described and definitely claimed.

In the accompanying drawings, forming 15 part of this specification:—

Figure 1 is a side elevation showing as closed the casing constituting the best practical embodiment of my invention of which I am cognizant.

Figure 2 is a transverse section taken in 20 the plane indicated by the line 2—2 of Figure 1.

Figure 3 is a top plan view illustrative of 25 the fastening comprised in my improvement.

Figure 4 is a longitudinal vertical section 30 of the said fastening.

Similar numerals of reference designate 35 corresponding parts in all of the views of the drawings.

The major portion of my improved casing is formed, by preference, of aluminum, but this, of course, is not of the essence of my invention, it being within the purview of the invention to form the casing of any material or materials best suited to its purpose.

Among other elements the casing comprises a body 1 which may be of any length in the discretion of the manufacturer, according to the length of the spirit level to 40 be carried in and protected by the casing. The said body 1 is closed at one end and open at its opposite end, and its open end is designed to be closed through the medium of a closure member 2 hingedly connected 45 at 3 to the end of the body and having side flanges 4 and an end flange 5, the said flange 5 being located at a point remote from the hinge connection, and the ends of the side flanges 4 being beveled as designated by 6 in 50 order to permit of free movement of the closure member to and from the position shown in Figure 1. Manifestly in the said position the closure member 2 will effectively exclude dust and dirt as well as moisture from the spirit level contained in the

case, and at the same time will protect the case against injury due to shock and jar.

Appropriately fixed to the closure member 2 and extending from the free end thereof is a standard 6', on which is a pivotally connected tongue 7, from which projects a pin 8 in which is a notch or kerf 9, Figure 4. The said tongue 7 is designed to be swung to and from the position shown in Figures 1 and 4, and is also designed to be 65 employed in conjunction with the novel and advantageous keeper means best illustrated in Figure 4. In addition to a casing 10 having an opening 11 and a slot 12, the keeper means comprises a keeper member 13, backed 70 by a spring 14; and having a finger piece 15 the shank of which is movable in the before mentioned slot 12. The aperture 11 receives the pin 8 as illustrated, and the free end of the pin being rounded or beveled as shown, 75 the introduction of the pin through the aperture 11 will be attended by backward movement of the keeper 13 against the action of its spring, followed by the forward snapping or movement of the keeper 13 into the 80 notch 9 for the strong holding of the tongue 7 in closed position, and for the retention of the closure member 2 in closed position and in such state that dust and moisture will be precluded from gaining access to the interior of the casing and bringing about injury to the spirit level contained in the said casing. On retraction of the keeper member 13 through the medium of its finger piece 15, the pin of the tongue 7 will be 85 released, and when the said tongue 7 is released and is swung upwardly and outwardly, it will be manifest that the closure member 2 may be conveniently swung open for the ready removal of a spirit level from 90 the casing. In the casing 10 is a well 16, and in said well is a coiled spring 17 on which is superposed a follower 18, said follower 18 being freely movable in the well 16. When the tongue 7 is closed and its pin 100 8 is introduced through the aperture 11, the said pin by acting against the platform 18 and depressing the same, operates to put the spring 17 under considerable tension. From this it follows that when the keeper member 13 is retracted as before described, the tongue 7 will be thrown promptly into open position where it may be conveniently grasped for the opening of the closure member 2.

It will be apparent from the foregoing that I have provided a simple, inexpensive and strong casing through the medium of which a spirit level or the like may be carried in such manner that the spirit level will be adequately protected at all times, and will be available for use when needed, the facility with which my casing may be opened for the removal of a spirit level and closed 10 after a spirit level is placed in the casing, being of the essence of my invention. It will also be appreciated that the fastening means employed is not only strong and well adapted to withstand the rough usage to 15 which tool appurtenances are ordinarily subjected, but the fastener construction is compact, and therefore lends itself to the storage of a number of casings of my invention in a space of small compass as is always 20 desirable.

While my novel casing is designed more especially to contain and protect a spirit level or the like, I would have it distinctly understood that my invention is not limited 25 to a casing for the specific purpose ascribed, the casing of my invention being put to any use to which it is applicable and being made, therefore, in various shapes and sizes.

I have entered into a detailed description 30 of the preferred embodiment of my invention in order to impart an exact understanding of all of the details of said embodiment. I do not desire, however, to be understood as confining myself to the specific construction disclosed, my invention being defined by 35 my appended claims within the scope of which changes in structure and arrangement may be made without departure from my invention.

Having described my invention, what I 40 claim and desire to secure by Letters-Patent, is:—

1. The combination of a casing body, a

closure member hingedly connected at one end to said body and having side flanges with 45 beveled ends and an end flange, the latter at the end remote from the hinge, a standard fixed to said closure member, a tongue pivotally connected to said standard and having a lateral pin with a beveled or 50 rounded end and with a notch or kerf in its side, a casing exterior of and fixed to the casing body and having an aperture in one of its walls and a slot in rear of said aperture, a well in said casing, a spring in said 55 well, a follower superposed on and movable by the spring and adapted to be opposed to the end of the pin on said tongue, and a reciprocatory keeper member, spring backed and movable in the casing and into and out 60 of engagement with the pin on the tongue and having a finger piece movable in the slot of the casing wall, the said finger piece being arranged at the opposite side of the tongue with reference to the pivotal connection of said tongue to the standard on the 65 closure member.

2. A casing comprising a body open at one end, a closure member hingedly connected to 70 said body, said closure member constructed and arranged to break joints with the body, a swingable tongue carried by the closure member and having a lateral pin with a beveled or rounded end and also with a notch or 75 kerf in its side, a casing on the body and exterior thereof and adapted to receive said pin, a spring pressed follower in said casing for impelling the pin and tongue, and a spring backed manually operable keeper member in the casing for automatically engaging and holding the pin on introduction 80 of the latter into the casing.

In testimony whereof I affix my signature.

GUNELIUS SKAVSTRAND.
